UNITED STATES PATENT OFFICE.

ALFRED J. KRANK, OF ST. PAUL, MINNESOTA.

ADJUSTABLE POWDER DISPENSER.

Application filed August 24, 1925. Serial No. 51,950.

5 My invention relates to an adjustable powder dispenser wherein I provide a powder and puff compact of a design to permit the powder to be carried in a loose form so that it can be dispensed readily when it is desired directly on to the puff and without loss, which permits the dispenser to be made small and compact, a feature which is very desirable in an article of this nature.

10 My invention includes means for dispensing the powder by a dispensing cup which may be rotated in either direction, and as the cup is rotated the powder is pushed through small openings directly in contact

15 with the powder puff. This permits just the exact amount of powder as is desired to be dispensed unto the puff and prevents the powder from being spilled out of the compact when the cover of the compact is

20 opened. The use of loose powder in a compact is most desirable as it does not become injured by dropping the compact, which is the case where the powder is in the cake form. The powder cannot ordinarily come out of the compact unless the dispensing cup is operated. This provides means of economizing in the use of the powder and thus only a small amount of powder is required to be carried in the powder compact.

25 It is also a feature of my invention to provide a dispensing cup which includes means for holding the powder puff so that it cannot fall out of the compact when the cover of the same is opened. This means of holding

30 the powder puff is very desirable as it permits the compact to be opened at any time without danger of the puff falling out and without danger of spilling the powder when the compact is opened. In this manner the powder puff is held in the dispensing cup, sealing the powder from the mirror side of the compact and keeping the mirror practically free from powder dust under ordinary circumstances.

35 I include in my invention means for holding and causing to hold the powder in the powder compartment against rotation when it packs in the powder compartment. This permits the powder to be engaged and compressed by the dispensing cup to force the powder through the openings in the dispensing cup when the cup is rotated, and as the powder is dispensed, the cup is pressed down into the powder compartment.

40 45 50 55 My powder dispenser is adjustable in the amount of powder dispensed unto the

puff and separable so that powder can be renewed into the powder compartment. The construction of my powder dispenser is extremely simple and operates in an effective manner with small compact parts so that my powder dispenser is made up in a small, thin, flat state, yet carrying an ample supply of powder and having a most desirable puff holding means.

60 65 All of the features and objects will be more fully set forth in the specification and claims.

70 In the drawings forming part of my specification;

75 Figure 1 is a side view of my compact in enlarged formation.

Figure 2 is a cross section on the line 2—2 of Figure 1.

Figure 3 is an enlarged perspective view 80 of the dispensing cup removed from the powder dispenser.

Figure 4 illustrates the operating ring of the dispensing cup.

Figure 5 illustrates the dispensing cup in 85 a plan view with the operating ring removed.

Figure 6 is a plan view of the inside of the bottom of my powder dispenser.

Figure 7 is a similar view to Figure 6, 90 illustrating a different formation embossed in the bottom.

95 My adjustable powder dispenser A is formed with a top 10 and a bottom portion 11 which parts are hinged together at 12 in the ordinary well known manner, so that the top 10 fits over the bottom 11 to close the compact A when not desired for use. The drawings illustrate the compact in an enlarged formation to more clearly illustrate the parts.

100 My adjustable powder dispenser A is provided with a mirror 13 in the cover portion 10 which is held by the ring 14 in the ordinary well known manner. The mirror portion 11 of the powder dispenser A is embossed in the bottom wall 15 thereof to provide an irregular design, such as a star 16, or the serrations 17, projecting up into the powder compartment 18. This embossed surface or formation, such as 16 or 17 in the powder compartment 18, forms means for engaging the powder held in the compartment 18 to prevent it from packing and rotating in a mass in the operation of 105 my dispenser.

110 I provide a dispensing cup 19 which is

provided with a series of openings 20 of a small, triangular shape formed by piercing the metal forming the bottom 21 of the dispensing cup 19, and leaving the metal which 5 is punched out to form the openings 20 projecting into the powder cutting points, such as 22. These points extend from each opening 20 and project into the powder compartment 18. The points 22 are sharp and cut 10 the powder as the dispenser cup 19 is rotated.

The powder dispensing cup 19 is provided with an operating ring 23, which is rigidly attached to the powder cup 19 by the depending flange 24, and which is provided with a horizontally extending flange 25 to form an engaging shoulder across the top and about the entire dispensing cup 19. The upper surface of the flange 25 is formed 20 with serrations 26 or is gnarled in a suitable manner so as to roughen the flange 25 so that it may be easily engaged by the fingers to rotate the dispensing cup 19.

The operating ring 23 is secured to the dispensing cup 19 in any suitable manner and may be formed integral therewith if it is desired.

The flange 25 of the ring 23 forms an important feature of my invention as it provides an annular shoulder which engages about the periphery of the powder puff B to hold the same against free disengagement from the dispensing cup 19. It will be quite apparent that this is important because upon opening the cover 10 of the compact A, unless the puff was held against disengagement it would be apt to fall out if the compact were tilted accidentally, and in this way the powder puff would become soiled, 40 which is very objectionable in powder compacts. The fact that my powder puff B is held against disengagement from the dispensing cup 19 also provides a very desirable feature, as it holds the puff B against the openings 20 and prevents any powder from being spilled out of the dispensing cup under ordinary circumstances.

In operation my adjustable powder dispenser compact is very desirable for use as 50 the mirror 10 is kept practically clear of any loose powder, the puff being held under the flange 23 in place in the dispensing cup 19. The dispensing cup 19 frictionally engages the side wall of the powder compact 18 and 55 is held against free engagement therefrom, but is sufficiently free to be rotated so that the powder from the compact 18 can be cut by the points 22 and pushed through the openings 20 when the operating ring 23 is 60 engaged on the serrated surface 26 to rotate the dispensing cup 19 in either direction and cause the desired amount of powder to be

dispensed unto the puff from the compartment 18.

When the desired amount of powder has 65 been dispensed to the puff B, the puff B is readily removed by engaging the puff strap 28, disengaging the puff from the dispensing cup 19 from under the flange 25. As the puff is removed from the cup 19, it having 70 collected all of the powder dispensed through the openings 20, the dispensing cup is left empty and the openings 20 being small, practically no powder will fall out through these openings, and thus I provide 75 a very economical and practical means of holding powder in a compact and for adjusting the same to dispense the desired amount of powder by the rotation of the dispensing cup 19 and by holding the puff 80 against dropping out of the cup 19 by the flange 25. The dispensing cup 19 is rotated until the powder compartment 18 is practically empty and at this point the dispensing cup has penetrated into the compartment 85 18 until the flanges 29 on the outer edge of the cup 19 engage the top of the bottom 11. The dispensing cup 19 then can be removed by engaging the flanges 29 to raise the cup 19 out of the compartment 18 and permit 90 the compartment 18 to be filled with powder.

The drawings illustrate a particular formation of my adjustable powder dispensing compact and I have illustrated and described my invention in accordance with the patent statutes, but I desire to have it understood that these drawings are only illustrative of a particular means of carrying out my invention and that the invention can be 100 applied to uses other than those above set forth and carried out by other means within the scope of the following claims.

I claim:

1. An adjustable dispenser having, a top 105 and bottom member; said bottom member being adapted to form a compartment for loose powder, means formed in the bottom member to prevent the powder from slipping therein, a dispensing cup carried by 110 said bottom member and an engaging surface formed on said dispensing cup to permit the rotation of the same in either direction to dispense powder through the cup from said powder compartment.

2. A compact for powder including, a casing, a dispensing cup within said casing, puff holding means within the cup to prevent free disengagement of the puff from the cup and a serrated surface within the 120 casing to hold the powder stationary in the same when the dispensing cup is rotated in the casing.

ALFRED J. KRANK.
